(57) CLAIM

The ornamental design for a racecar bobble novelty, as shown and described.

DESCRIPTION

FIG. 1 is a front perspective view of an ornamental design of a racecar bobble novelty showing my new design.

FIG. 2 is a front side elevational view thereof.

FIG. 3 is a rear side elevational view thereof.

FIG. 4 is a right side elevational view thereof.

FIG. 5 is a left side elevational view thereof; and,

FIG. 6 is a top plan view thereof.

The broken lines shown in FIGS. 1-5 illustrate portions of the racecar bobble novelty and form no part of the claimed design.
